ALMYR L. NEWMAN, OF WARWICK, RHODE ISLAND

FLEXIBLE BAND, CHAIN, OR LINKAGE

Application filed March 2, 1928. Serial No. 258,606.

This invention relates to improvements in flexible bands, chains or linkages used as articles of jewelry, particularly as bracelets for attachment to wrist-watches.

5 A principal object of the invention is to provide an article of the type specified comprising articulated link-elements adapted to flex one in relation to the other and to slide one on another to render the band or linkage flexible and expansible to fit the wrist of the wearer when used as a bracelet.

Another object of the invention is to provide a band or linkage having the link-elements coupled together in such manner that 15 they may be readily disconnected so that one or more units can be added to or subtracted from the bracelet to adjust its length as required.

Another object of the invention is to provide 20 a device of the type specified wherein the link-elements may be constructed from sheet-metal blanks punched out and struck up in dies and capable of being assembled with smooth, neat joints.

25 Another object of the invention is to provide a device of the type specified in which the coupling means for the link-elements is strong and sturdy and not liable to become accidentally disconnected, while at the same 30 time being susceptible of convenient and easy detachment to allow the adjustment in the length of the band or bracelet.

Further objects of the improvement are set forth in the following specification which 35 describes a preferred form of construction of the invention as illustrated by the accompanying drawings. In the drawings:

Fig. 1 is a perspective view illustrating a 40 wrist-watch band or bracelet embodying the present invention and showing it flexed in circular shape and contracted with its links in telescoped relation;

Fig. 2 is a greatly enlarged bottom plan view of several of the associated link-elements 45 shown partly in section on the line 2-2 of Fig. 3 and illustrating one of the inner links as drawn out in extended or expanded relation;

Fig. 3 is an enlarged cross-sectional view 50 of several of the links taken on the line 3-3

of Fig. 2 and illustrating the method of releasing the connecting means to detach the link-elements;

Fig. 4 is a perspective view showing two 55 of the assembled link-units and illustrating the means by which their ends are connected;

Fig. 5 is a composite perspective view showing one of the inner slide links and illustrating its tongue or latch as removed therefrom; 60

Fig. 6 is a plan view of the slide link showing a modified form of the tongue therefor and the method of connecting it with the end 65 of the inner link.

The present improved band, chain or linkage comprises in general a series of outer tubular box-links 2 assembled with inner 70 slideable connecting-links 3 which are normally maintained telescoped within the box-links under the tension of suitable coil-springs. The outer or main box-links 2 are preferably constructed from sheet-metal blanks which are folded to form a substantially flat unbroken top-portion 5 with sides 6 bent at right-angles thereto, and a bottom-portion formed by extensions 7 of the sides 75 folded over to meet at the center; it being noted that in Figs. 2 to 6 of the present drawings the several link-elements are shown in inverted position, or bottom side up, as compared with the position they assume when applied to the bracelet or other similar article.

As shown most clearly in Figs. 3 and 4, the sides 6 of the outer box-link 2 are extended 80 at one end to form rounded ears 8 which are pierced or otherwise formed with holes for receiving the ends of a cross-bar or pin 9. The opposite ends of the sides 6 of the box-link 2 are cut away or recessed at 10 with a rounded contour to adapt them to receive the edges of the ears 8 on the next adjacent box-link when the link-elements are assembled 85 end-to-end in abutting relation as shown in Fig. 1.

At the end of the box-link 2 carrying the pin 9 are two tabs or prongs 11 projecting from the edges of the folded bottom-strips 7 in spaced-apart relation and bent over in 90 arcuate shape to partly surround and bear 95 100

against the side of the pin 9 as shown in Fig. 4. These two ears or prongs 11 serve as a reinforcement for the pin 9 whereby to hold it from buckling or bending so that it is prevented from pulling out of the ears 8.

At the opposite end of the box-link 2 are two similar ears or prongs 15 bent inwardly to stand at right-angles to the bottom-strips 7, and spaced apart at the center to provide an opening 16 for a purpose as later explained.

The inner slide links 3 are constructed in the form of a shallow tray, see Fig. 5, having a flat top-portion 17 with sides 18 bent at right-angles thereto and a cross-strip 19 bent over from the end thereof. At the opposite end the top of the slide projects forwardly beyond the sides 18 and is curled around to form a hook 20 extending the full width of the slide link. The hook 20 is adapted to be hooked around the cross-bar or pin 9 at the end of the next adjacent box-link to engage the full width thereof and a tongue or latch-member 21 is assembled with the slide link in position to adapt its end to impinge against the side of the pin or cross-bar to prevent its disengagement from the hook.

As illustrated in Figs. 2 and 5 of the drawings the tongue or latch 21 is constructed in the form of a substantially flat strip of sheet-metal having a widened portion 22 at one end adapted to fit within the sides 18 of the slide link 3 with a slight clearance therebetween and provided with lateral ears 23 which are received in the openings 24 between the edges of the sides 18 and the end-strip 19. The forward end of the tongue 21 is bent or curled upwardly to a slight extent to bring it into position to engage somewhat above the center of the cross-pin 9 when the latch is assembled with the slide link as shown in Fig. 3.

A relatively flat helical spring 25 is arranged to enclose the latch or tongue 21, fitting quite snugly around its widened portion 22 to bear against the edges of its lateral ears 23 and extending forwardly nearly to the opposite end of the tongue. When the tongue or latch 21 is placed within the slide link 3 with its lugs or ears 23 seated in the openings 24 and the slide inserted in the box-link 2 the spring 25 will be compressed with its forward end bearing against the inturned prongs 15 as illustrated at the left in Fig. 3, the method of assembling the links being as later explained.

A modified form of the slide link and its tongue is illustrated in Fig. 6 which shows the sides 28 of the slide link 30 as being extended rearwardly into abutting relation with the end-strip 29. In this form of construction the end-strip 29 is formed with a central opening 31 adapted to receive a pair of prongs 32 which project from the rearward end of the

tongue 33. The two prongs 32 are formed from a substantially dovetailed strip made integral with the tongue or latch 33, as indicated by the dotted lines in Fig. 6, and are bent apart and folded over against the side of the end-strip 29 to provide a rivet-like connection between the tongue and the slide link.

Referring to Fig. 5, the edges of the sides 18 on the slide link 3 are preferably notched with slight indentations 35 which may be engaged by the finger-nail when the slide link is drawn outwardly as shown at the right in Fig. 3, so that the slide may be held in this extended relation to facilitate the uncoupling of the link-units in the manner as hereinafter more fully explained.

In assembling the several units of the band, chain or linkage the springs 25 are first placed on the tongues or latches 21 and the latter applied to the slides 3 by inserting their lateral ears 23 in the openings 24.

The box-links 2 have their pins 9 inserted through the ears 8 and riveted over at their ends and the prongs 11 are then bent down across the side of the pins to hold the latter in place and reinforce them against bending. The forward prongs 15 on the box-links 2 are left without bending until the slide links 3 are assembled therewith. Each slide link 3, assembled with its connected latch or tongue 21, is slid into its respective box-link 2 with the spring 25 in place on the tongue, and the prongs 15 are then bent inwardly to engage the end of the spring as shown in Fig. 3.

After the several elements of the link-unit have been assembled in the manner as above described they are coupled together by hooking the hooks 20 around the cross-pins 9. This is accomplished by turning one link-unit to stand at substantially right-angles to the next unit, as indicated at the right in Fig. 3, and then carrying them together with the cross-pin 9 pressed down against the end of the tongue 21 to cant the latter whereby to allow the pin to slide into place within the hook 20. After the pin 9 on one link-unit is engaged with the hook 20 on the next adjacent unit in this manner the links may be turned into alined relation, whereupon the end of the tongue 21 will slide upwardly into position slightly above the center of the pin. It will be understood that the slide link 3 is drawn out from the end of the box-link 2 as shown at the right in Fig. 3 during this operation of coupling the links together and with the links in this relation the spring 25 is compressed so that the forward end of the tongue 21 may be canted away from the edge of the hook.

When it is required to uncouple the links to remove one or more units or to add other units to the band or bracelet the operation is performed as follows: No special tools

are required, but, conveniently, a pin 40 or other sharp instrument is used to press the end of the tongue 21 into position as shown at the right in Fig. 3 to release the pin 9 from the hook 20. As before noted, the slide link 5 may be held in extended relation during this operation by inserting the finger-nail in the notches 35, and after the end of the tongue 21 has been depressed the connected box-link is canted at an angle and its pin 9 released 10 from engagement with the hook 20 on the slide link. It will thus be seen that the link-units may be connected and disconnected very conveniently and expeditiously by anyone not especially skilled as a mechanic. 15 Through this provision link-units may be subtracted from or added to the bracelet to adjust its length to the wrist of the wearer without requiring that the article be sent back to the manufacturers or to an expert 20 workman for this purpose.

It is to be particularly noted that the present improved construction of the box-link provides for reenforcing the cross-pin or connector which couples the link with the next 25 slide link and this is an important feature as making for greater strength and sturdiness in the completed article. Heretofore where cross-pins have been employed for coupling 30 together the parts or units of a bracelet they have been open to the objection that due to the slenderness of the pins they would buckle and bend and become loosened or disengaged at their ends. It is a maxim that "a chain 35 is no stronger than its weakest link" and bracelets or like articles constructed in the manner described have heretofore been extremely weak and liable to rupture or breakage at this point. In the present construction the curved prongs 11 take the side 40 thrust on the pin 9, thus preventing it from bending or buckling and thereby greatly increasing the strength of the bracelet at this vulnerable point.

As another feature of improvement, it is 45 to be noted that the slide link has a relatively wide hook-portion which engages with the cross-pin throughout the whole length of the latter, thus increasing the strength and stiffness of the hook and removing the liability 50 of its becoming bent or straightened out. The bracelet or other article is thus rendered stronger and more durable at this point of connection between the links.

As still another feature of the improvement 55 the tongue or latch 21 is held solidly against the end-strip of the slide link 3 so as to prevent a loose or shakily joint and its forward end which extends across the side 60 of the pin 9 is held in the opening between the prongs 11 of the box-link so as to prevent unwarranted side play or looseness.

Due to the above mentioned features the 65 whole bracelet is of much stronger and sturdier construction than those heretofore em-

ployed for like purposes and the completed article has much greater durability in use. The coupling-means or connection between the link-units is also made secure and proof against accidental or unwarranted dislocation so that the bracelet is superior in this respect to others heretofore used. 70

While I have herein shown and described the improved device as embodied in a preferred form of construction it is to be understood that various modifications may be made in the structure and arrangement of its parts without departing from the spirit or scope of the invention. 75

Therefore, without limitation in this respect, I claim:

1. In a device of the type specified, the combination of box-links having cross-pins extending between their sides at the open end thereof and integral tabs projecting from the 85 end of the links and bent around the cross-pins to reinforce the latter, slides slidable in the box-links and formed with hook-portions projecting from the end thereof to hook around the cross-pins on the next adjacent box-links, 90 and latches carried by said slides and adapted to cooperate with their hooks to retain them in engagement with the cross-pins.

2. In a device of the type specified, the combination of a box-link having a relatively flat 95 top with sides bent at right-angles thereto and bottom-portions folded inwardly therefrom, a cross-pin extending between the sides of the box-link at the open end thereof, tabs formed by extensions of the bottom-portions 100 of the link bent to partly enclose the cross-pin to reinforce the latter and spaced at a distance apart therealong, a slide having a relatively wide hook-portion adapted to be hooked around the cross-pin on the box-link between 105 its sides, and a latch on the slide having a relatively narrow end-portion projecting between the reinforcing tabs in position to engage the cross-pin to maintain the hook on the slide in engagement therewith. 110

3. In a device of the type specified, the combination of a box-link having a top-portion, sides bent at right-angles thereto and bottom-portions folded inwardly therefrom with integral tabs projecting from the bottom-portions 115 and bent into arcuate shape, a pin riveted through the sides of the box-link at the open end thereof and arranged to bear against the arcuate tabs to be reinforced thereby, a slide-link formed with a relatively wide hook at its end adapted to hook around the cross-pin in the box-link, a latch-member rockably held within the slide with its end projecting between the reinforcing tabs in position to retain the hook in engagement with the cross-pin, and a spring operating on the latch to normally hold its end in cooperative relation with the hook. 120

4. In a device of the type specified, the combination of a box-link having a cross-member 130

at its end, a slide link slidable within the box-link and provided with a hook at its end for engaging the cross-member on the next adjacent box-link of a series, a relatively flat latch held within the slide abutting its end-portion, and a spring enclosing the latch and acting between the slide and the box-link to maintain them in telescoped relation, said spring acting on the latch to maintain its end in cooperative relation with the hook to retain the latter in engagement with the cross-member of the next link in the series.

5. In a device of the type specified, the combination of a box-link having a cross-member at its end, a slide slidable within the box-link and provided with a hook at its end adapted to engage the cross-member on the next adjacent box-link of a series, said slide having sides and a lateral end-strip with 10 openings therebetween, a latch having a portion fitting between the sides of the slide and lugs projecting laterally therefrom to be received in the openings between the sides and the end-strip, and a helical spring enclosing the latch and acting against the latter to hold it in position in the slide and to maintain the slide in telescoped relation with the box-link, said spring being normally extended along the latch to hold it in position 20 to maintain its end in cooperative relation with the hook on the slide to retain the latter in engagement with the cross-member of the adjacent box-link while adapting it to be released therefrom.

35. 6. In a flexible band, chain or bracelet, the combination of box-like link-elements having cross-members at one end, slides slidable in the box-links and provided with hooks at their ends adapted to hook over the cross-members of adjacent box-links to couple the link-elements in articulated relation, latches carried in the slides with their ends adapted to cooperate with the hooks to retain the latter in connected relation with the cross-members 40 on the box-links, and helical springs coiled around the latches and acting thereagainst to maintain the slides telescoped within the box-links, said springs when in extended relation acting on the latches to maintain their ends in cooperative relation with the hooks to retain the latter in engagement with the cross-members.

7. In a device of the type specified, the combination of box-links having cross-members extending between their sides at the open end thereof, slides slidable in the box-links and formed with hook-portions projecting from the end thereof to hook around the cross-members on adjacent box-links, latches 55 carried by said slides, helical springs coiled around the latches and acting thereagainst to hold them against the ends of the slides, said springs acting to maintain the slides telescoped within the box-links and when extended along the latches acting to maintain

the latter with their ends overlapping the cross-members whereby to retain the hooks on the slides in connected relation with the cross-members on the box-links.

8. In a device of the type specified, the combination of a hollow box-link having a pin extending across its open end, a slide slid- 70 able within the box-link and formed with a cross-strip at one end and a hook at its opposite end adapted to hook around the pin of an adjacent box-link, a latch having its end seated against the end-strip of the slide and formed with a tongue arranged with its end in opposite relation to the hook on the slide, a helical spring enclosing the tongue 75 of the latch and acting against its end to press the latter against the end-strip of the slide, and also acting against the end of the box-link to maintain the slide in telescoped relation with respect thereto, said spring tending to normally maintain the tongue of the latch spaced from the top of the slide to hold it in position to engage the pin on the adjacent box-link to prevent the hook on the slide from being accidentally uncoupled therefrom.

9. In testimony whereof I affix my signature.
